EDWARD EHLERS, OF ROCKAWAY, NEW JERSEY

TIE FOR REINFORCING RODS

Application filed November 25, 1929. Serial No. 409,501.

This invention relates, generally, to reinforced concrete construction; and the invention has reference, more particularly, to improved means for securing assembled angularly arranged reenforcing rods in desired relative positions preparatory to concrete forming, said means consisting of a novel unitary tie or clip.

Heretofore, unitary reenforcing rod ties generally used have been either insufficiently rigid to positively retain assembled reenforcing rods in desired relative angular positions or in instances where such ties possess the necessary rigidity, they have been difficult or almost impossible to apply in use to the reenforcing rods.

The principal object of the present invention is to provide a novel unitary tie for reenforcing rods which tie not only positively and rigidly retains the connected reenforcing rods in desired relative angular positions, but which is also easily applied to the reenforcing rods.

Another object of the present invention lies in the provision of a tie of the above character which is of simple, cheap construction and comprises a unitary wire or rod member having a loop portion adapted to partially surround one reenforcing rod and to press said rod against another such rod disposed crosswise of said first rod, said member having offset leg portions extending in opposite directions from said loop portion and along one side of said second named rod, said leg portions being of unequal lengths and terminating in aligned hooks, said hooks partially surrounding said second rod and urging the same toward said first rod.

Other objects of this invention, not at this time more particularly enumerated, will be clearly understood from the following detailed description of the same.

The invention is clearly illustrated in the accompanying drawings, in which:—

Fig. 1 is a fragmentary perspective view of crossing reenforcing rods secured together by the novel tie of this invention;

Fig. 2 is a plan view illustrating the man-

ner of assembling a plurality of reenforcing rods;

Fig. 3 is a sectional view in end elevation of a fragment of the structure of Fig. 2; and Fig. 4 is a perspective view of the novel tie of this invention.

Similar characters of reference are employed in all of the hereinabove described views to indicate corresponding parts.

Referring now to said drawings, the reference characters 6 and 7 designate reenforcing rods which are crossed by similar rods 8 and 9, the said rods being held in fixed relative positions by ties constructed according to and embodying the principles of the present invention. Each of these ties comprises a loop 10 which is adapted to fit snugly over a reenforcing rod in gripping relation therewith, for example, reenforcing rod 6. The loop 10 extends at an oblique angle with respect to the longitudinal axis of the reenforcing rod 6, and bight portion 11 of this loop is thereby positioned so as to press the rod 6 directly against underlying rod 9. The sides of the loop 10 terminate in offset shanks 12 and 13 which have their lower portions abutting a side of the rod 9. Shank 12 has a leg portion 14 formed on its lower portion which shank extends substantially parallel along the side of the rod 9 and terminates in a hook 15 which passes around the underside of this rod in gripping relation therewith and presses upwardly upon rod 9. Shank 13 is also provided with a leg portion 16 which is of greater length than leg portion 14 and extends in a direction substantially opposite to that of leg portion 14. Leg portion 16 also terminates in a hook 17 which passes around the underside of reenforcing rod 9 in gripping relation therewith, and which also presses upwardly upon rod 9.

Leg portions 14 and 16 are resilient and urge hooks 15 and 17 upwardly and towards the bight portion 11 of loop 10. When the tie is not assembled upon a reenforcing rod, the leg portions 14 and 16 extend substantially in opposite directions and somewhat upwardly from the point of connection with their shanks 12 and 13 so that they form acute angles with their respective shanks as espe-

cially illustrated in Fig. 4. In the act of assembling the tie upon the reenforcing rods, the loop 10 is forced somewhat away from the hooks 15 and 17, causing a deflection of the leg portions 14 and 16 so that when assembled on the rods they are aligned and extend substantially at right angles to their respective shanks and parallel to the reenforcing rod 9. This deflection of the leg portions causes them to urge hooks 15 and 17 toward the bight portion 11 of the loop 10 thereby firmly pressing one rod directly against the other. The plane of pressure of the bight portion 11 extends directly through the longitudinal axes of the hooks 15 and 17, thereby eliminating any rotative tendency of the connected reenforcing rods and rigidly holding one crosswise of the other.

In assembling the reenforcing rods by use of the ties, each tie is held preferably by the leg portion 16 and is placed upon the rod 9, for example, so that hook 15 engages the underside of this rod with the loop 10 positioned over the other rod 6. Leg portion 16 is then manipulated so that the loop 10 engages the sides and upper surface of rod 6, whereupon leg portion 16 is pressed downwardly and inwardly with respect to rod 9, causing hook 17 to engage the underside of this rod, there-by locking the two rods together in crosswise relation. The downward movement of leg portion 16 also causes the sides of loop 10 and shanks 12 and 13 to move toward one another and into gripping relation with the sides of rod 6. Preferably, consecutive ties are staggered as illustrated in Fig. 2, so that the leg portions of one tie are positioned on the opposite side of rod 9 with respect to the leg portions of the next succeeding tie.

Owing to the obliqueness of the loop 10 with respect to rod 6, the sides of this loop obtain a firm hold upon this rod which hold extends for a distance along the length thereof, thereby greatly adding to the rigidity with which the rod 6 is held by the loop. The greater length of the leg portion 16 over that of leg portion 14 enables the ready insertion of the hook 17 under the reenforcing rod 9.

The relatively great spacing of the hooks 15 and 17 enables the tie to obtain a firm hold on rod 9 which together with the firm hold of the oblique loop 10 upon rod 6 in addition to the existence of a direct line of pressure between the bight portion 11, the intersecting axes of rods 6 and 9 and the hooks 15 and 17, all combine to cause the novel tie of this invention to rigidly hold the connected rods in fixed relative positions.

The greater length of the leg portion 16 over that of leg portion 14 enables the ready and easy application of the tie to reenforcing rods or the removal of the tie therefrom if desired.

As many changes could be made in the above construction and many apparently

widely different embodiments of this invention could be made without departing from the scope thereof, it is intended that all matter contained in the above description or shown in the accompanying drawings shall be interpreted as illustrative and not in a limiting sense.

What is claimed is:—

1. In combination a pair of intersecting concrete reenforcing rods and a tie therefor comprising, a loop extending around a portion of one of said rods and acting to directly press said rod against the second of said rods, shanks formed on said loop and terminating adjacent a side of said second rod, oppositely extending leg portions of unequal lengths formed on said shanks and hooks provided at the ends of said leg portions and partially surrounding said second rod and urging the same toward the first of said rods.

2. In combination a pair of intersecting concrete reenforcing rods and a tie therefor comprising, a loop extending around a portion of one of said rods and disposed obliquely to the longitudinal axis thereof and having its bight portion pressing said rod directly against the second of said rods, shanks formed on said loop and terminating adjacent a side of said second rod, oppositely extending leg portions of unequal length formed on said shanks and hooks provided at the ends of said leg portions and partially surrounding said second rod and urging the same toward said first rod and said loop, the lines of pressure of said hooks and said bight portion lying in a common plane with the longitudinal axis of said second rod.

In testimony, that I claim the invention set forth above I have hereunto set my hand this 8th day of November, 1929.

EDWARD EHLERS.
